UNITED STATES PATENT OFFICE.

JAMES K. DALTON, OF WAVERLY, OHIO.

AIR-PUMP.

1,117,001.

Specification of Letters Patent.

Patented Nov. 10, 1914.

Application filed February 25, 1914. Serial No. 820,980.

To all whom it may concern:

Be it known that I, JAMES K. DALTON, a citizen of the United States, residing at Waverly, in the county of Pike and State 5 of Ohio, have invented new and useful Improvements in Air-Pumps, of which the following is a specification.

The invention provides an air compressor particularly designed for motor vehicles for 10 inflating tires and charging tanks or reservoirs with air under pressure, such compressor being coupled directly to one of the cylinders of the engine to be operated directly by the expansive force of the gases 15 during combustion.

The invention provides a mechanism of the character hereinbefore stated comprising a power cylinder and a compressor, said power cylinder being adapted to be coupled to an engine cylinder to be operated by the 20 expanding gases thereof and the compressor having its piston connected with the piston of the power cylinder to move therewith, the novelty residing chiefly in the peculiar construction and arrangement of the several parts whereby the air and gases are controlled in their inflow and outflow during 25 the operation of the invention.

The invention consists of the novel features, details of construction and combination 30 of parts, which hereinafter will be more particularly set forth, illustrated in the accompanying drawings, and pointed out in the appended claims.

Referring to the drawings, forming a 35 part of the specification, Figure 1 is a vertical central section of an air pump embodying the invention, showing the same coupled to the cylinder of an engine of the internal 40 combustion variety. Fig. 2 is a detail view of the upper portion of the air compressing cylinder. Fig. 3 is a top plan view of the air compressing cylinder. Fig. 4 is a sectional view on the line $\alpha-\alpha$ of Fig. 1.

Corresponding and like parts are referred 45 to in the following description, and indicated in all the views of the drawings, by the same reference characters.

The power cylinder 1 is closed at its lower 50 end by means of a cap 2 and at its upper end by means of a cap 19, said caps being secured to the cylinder in any manner. A short tube 4 is coupled to the cap 2 and connects the power cylinder with a plug 66, 55 which is threaded into the end or other part of the engine cylinder A. The lower end

of the tube 4 is finished to provide a valve seat against which a valve 8 closes, said valve being attached to the lower end of a stem 9, which passes through the cylinder 60 1. A cylinder 21 extends from the cap 19 in line with the cylinder 1, and preferably forms a part of the cap 19. The upper end of the cylinder 21 is made thick and heavy, as indicated at 22, and is closed at its upper 65 end, the latter having a central opening formed therein which is internally threaded to receive the upper end of a tube 11, the latter extending through the cylinder 21 and cylinder 1 and having a valve seat at 70 its lower end against which a valve 10 closes, said valve being loose upon the stem 9 and pressed against its seat by means of an expansive helical spring 7 mounted upon the lower end of the stem 9 and confined between 75 the valves 8 and 10. A piston 12 is arranged to operate in the cylinder 1 and is normally held at its lowest position in such cylinder by means of an expansive helical spring 18, which is arranged within 80 the cylinder 1 and confined between the cap 19 and piston 12. A tube 12^a extends upwardly from the piston 12 and is slidable upon the tube 11 and within the cylinder 21. The tube 12^a is of a length so that when the 85 piston 12 is at the limit of its down stroke the upper end of such tube is at the lower end of the cylinder 21. A washer 6 is located upon the inner side of the cap 2 and receives the impact of the piston 12 when 90 the same reaches the limit of its down stroke. The tube 12^a forms a hollow rod or stem for the piston 12 and its lower end is slightly enlarged and above such enlargement the tube 12^a is formed with an inner annular 95 extension 12^b, which engages the tube 11 and assists materially in directing the piston 12 in its reciprocating movements. A piston is provided at the upper end of the tube 12^a and is adapted to operate in the 100 cylinder 21 and serves upon the in stroke to draw a charge of air into the cylinder 21 and upon the outstroke to compress and force such air from the cylinder into the part to be charged. The upper end of the 105 tube 12^a is enlarged and an extension 12^c projects from such enlargement and is externally threaded to receive the internally threaded rim of a ring 13, which latter is approximately of a width to extend across 110 the space formed between the tube 11 and inner wall of the cylinder 21. A packing

ring 14 is located exterior to the rim of the ring 13 and a packing ring 15 is arranged upon the interior of the extension 12^a, both packing rings 14 and 15 being confined between edge portions of the ring 13 and the enlargement at the upper end of the tube 12^a. These several parts constitute elements of the piston located at the upper end of the tube 12^a, the packing rings 14 and 15 maintaining a close joint between the piston and the walls of the cylinder 21 and tube 11.

The tube 11 is threaded into the upper end of the thickened part 22 of the cylinder 21 and is made secure by means of a lock nut 23 threaded to the projecting end of the tube. It will thus be understood that the tube 11 is fixed. A cap 24 has a snug fit upon the thickened end 22 of the cylinder 21 and is rotatable upon the part 22 and is formed in its sides at opposite points with inclined slots 41 through which extend parts projecting outwardly from the thickened end portion 22 of the cylinder 21. The upper end of the stem or rod 9 is connected with the cap 24 and moves therewith. When the cap 24 is turned in one direction it is moved lengthwise of the cylinder 21, thereby unseating the valve 8 and when the cap 24 is turned in the opposite direction it moves outward upon the cylinder 21 to effect a seating of the valve 8. The longitudinal movement of the cap 24 is effected by the inclined slots 41 and the parts projecting through such slots. A tube 26 projects laterally from the cap 24 and receives a pin 31 which is slidable therein, the inner end of such pin being adapted to extend through an opening in a side of the cap 24 and enter one of two openings 32 formed in a side of the part 22, thereby holding the cap 24 in either one of its extreme positions. A washer 36 is secured to the outer end of the pin 31 and engages the outer end of a finger piece 25 which is slidable upon the outer end of the tube 26. An expansible helical spring 27 mounted upon the pin 31 normally exerts an inward pressure thereon to hold the inner end of such pin in either one of the openings 32. When the finger piece 25 is drawn outward the inner end of the pin 31 is disengaged from the part 22 of the cylinder, thereby admitting of the cap 24 being turned, said cap being secured in the required position, by entrance of the inner end of the pin 31 into the desired opening 32. The cap 24 has the upper end of the rod or stem 9 connected thereto, hence longitudinal movement of the cap effects a corresponding movement of the stem 9, whereby the valve 8 may be opened or closed. Openings 36 are formed in the upper end of the cap 24 for the ingress and egress of air when the compressor is not working. These openings are adapted to be closed by means

of a part 34, which is in the nature of a shallow cup, the bottom portion of which is formed with openings to register with the openings 36 in one position of the cup, but which close the openings 36 when such cup 34 is moved to a different position. The cup 34 is rotatably mounted upon the upper end of the rod or stem 9 and is formed at one side with an extension 33 to which a catch 33^a is pivoted, said catch being adapted to engage a part of the finger piece 25 so as to hold the cup 34 in a given position. The cup 34 is adapted to receive a small quantity of liquid fuel when it becomes necessary to prime the engine cylinder A, 80 said fuel passing from the cup through the tube 11 into the cylinder when the valve 8 is open, the valve 10 opening automatically on the suction stroke of the piston.

The cylinder 21 is provided at its upper end with an inlet and an outlet, the inlet being controlled by means of a valve 42 and the outlet by means of a valve 37. These valves may be of any construction and constitute the extensions which project from the part 22 of the cylinder and pass through inclined slots 41 of the cap 24. Upon the down stroke of the piston operating in the cylinder 21 air is drawn into such cylinder through the valve controlled inlet 42, the valves controlling the outlet 37 closing and upon the outstroke of such piston the valve controlling the inlet closes and the valve of the outlet opens. A flexible tube 48 is coupled to the valve 37 and is adapted to convey the air from the compressor to the required point of use.

When the valve 8 is seated the cylinder of the engine to which the device is coupled operates in the usual manner for driving the machine or the parts to be operated. Upon opening the valve 8 and closing the openings 36 the piston 12 is caused to move outward in the cylinder 1 when the gaseous mixture is ignited in the cylinder A, thereby moving the piston at the upper end of the tube 12^a outward in the cylinder 21. As the burnt gases exhaust from the cylinder A the piston 12 is moved downward in the cylinder 1 by the action of the spring 18, 115 thereby returning the piston operating in the cylinder 21 to the lower end thereof and drawing a fresh charge of air into such cylinder 21 to be forced therefrom at the next outward movement of the piston 12. 120 When the valve 8 is open and the openings 36 uncovered the air is drawn into the cylinder A through the openings 36, tube 11 and connection 4 and passes out through the exhaust of the cylinder A in the usual way. 125 The valve 10 opens to admit the air, but closes to prevent escape of the same through the tube 11. In this manner the cylinder A of the engine is cooled.

From the foregoing description taken in

connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:—

1. An air compressing device of the character specified comprising aligned power and air compressing cylinders, the latter being of less diameter than the former, a tube extending through the cylinders and connected at its outer end to the outer end of the air compressing cylinder, said tube having a valve seat at its inner end, a valve for closing the inner end of such tube, means for controlling the admission of air into the outer end of the before mentioned tube, a piston arranged to operate in the power cylinder, and a piston arranged to operate in the compressing cylinder and connected with the first mentioned piston to move therewith.

2. In air compressing means of the character specified the combination of aligned cylinders of different diameters, the smaller cylinder having a valve controlled inlet and a valve controlled outlet at its outer end, a tube extending through the two cylinders and connected at its outer end with the outer end of the smaller cylinder and provided at its inner end with a valve seat, a valve for closing the inner end of the tube, means for regulating the admission of air into the outer end of the said tube, a second tube slidable upon the first mentioned tube, a piston at the inner end of the second tube arranged to operate in the larger cylinder, and a second piston at the opposite end of the second tube and arranged to operate within the smaller cylinder.

3. In an air compressor of the character specified the combination of aligned cylinders, one of such cylinders having a valve controlled inlet and a valve controlled outlet and the other cylinder having a valve controlled outlet, a tube extending through the cylinders, a valve for closing the inner end of the tube, means for regulating the admission of air into the outer end of said tube, means for positively opening or closing the valve outlet of the second cylinder, and connected pistons arranged to operate in the respective cylinders.

4. In combination air compressing and power cylinders, the former having a valve controlled inlet and a valve controlled outlet and the latter having a valve controlled

outlet, means mounted upon the outer end of the air compressing cylinder and having connection with the valve for closing the outlet of the power cylinder, and connected pistons arranged to operate in the respective cylinders.

5. In combination aligned air compressing and power cylinders, the latter having a valve controlled outlet and the former having a valve controlled inlet and a valve controlled outlet, a tube extending through the cylinders and having a valve seat at its inner end, a valve for closing against the valve seat at the inner end of the tube, means for admitting air into the outer end of such tube, a stem extending through the tube and cylinders and connected with the valve controlling the outlet of the power cylinder, means mounted upon the outer end of the compressing cylinder and connected with said stem for operating the same to open or close the valve regulating the outlet of the power cylinder, and connected pistons arranged to operate in the respective cylinders and slidably mounted upon the before mentioned tube.

6. In combination a power cylinder having an outlet, an air compressing cylinder in line with the power cylinder and provided at its outer end with a valve controlled inlet and a valve controlled outlet, a tube extending through the cylinders and connected at one end with the outer end of the air compressing cylinder and provided at its inner end with a valve seat, a valve closing the inner end of the tube, a valve for closing the outlet of the power cylinder, a stem connected with the last mentioned valve and passing through the valve at the inner end of the tube and through the latter, means mounted upon the outer end of the compressing cylinder and connected with said stem to effect an opening or a closing of the valve at the outlet of the power cylinder, and connected pistons arranged to operate in the respective cylinders and slidably mounted upon the before mentioned tube.

7. In combination aligned air compressing and power cylinders, the latter having an outlet and the former being provided with a valve controlled inlet and a valve controlled outlet, a cap fitted to the outer end of the air compressing cylinder and having an inclined connection therewith, a valve for closing the outlet of the power cylinder, a stem connected with such valve and with the before mentioned cap, a tube extending through the cylinders and surrounding the stem and provided at its inner end with a valve seat and having connection at its outer end with the outer end of the air compressing cylinder, means for controlling the supply of air to the outer end of such tube, a spring actuated valve mounted upon the

- inner end of the stem and closing the inner end of the tube, and connected valves arranged to operate in the respective cylinders and slidably upon the said tube.
- 5 8. In combination alined air compressing and power cylinders, the latter having an outlet, valves fitted to the outer end of the air compressing cylinder for controlling the inlet and the outlet thereof, a cap rotatably 10 mounted upon the outer end of the air compressing cylinder and provided with inclined slots for the passage therethrough of the inlet and outlet controlling valves of such cylinder, a stem connected with the 15 cap and passing through the cylinders, a valve at the inner end of such stem for closing the outlet of the power cylinder, a tube

extending through the cylinders and having a valve seat at its inner end and connected at its outer end with the air compressing cylinder, means mounted upon the cap for regulating the admission of air into the said tube, a valve mounted upon the stem and closing the inner end of the tube, and connected pistons arranged to operate in the respective cylinders and slidably mounted upon the before mentioned tube.

In testimony whereof I affix my signature in presence of two witnesses.

JAMES K. DALTON.
